UNITED STATES PATENT OFFICE.

HENRY P. CLAUSEN AND WILLIAM T. CURTIS, OF CHICAGO, ILLINOIS, ASSIGNEES TO
SAMUEL C. SCOTTEN, TRUSTEE, OF CHICAGO, ILLINOIS.

CALL-REGISTER.

1,078,772.

Specification of Letters Patent. Patented Nov. 18, 1913.

Application filed March 15, 1910. Serial No. 549,482.

To all whom it may concern:

Be it known that we, HENRY P. CLAUSEN and WILLIAM T. CURTIS, citizens of the United States, residing at Chicago, county 5 of Cook, State of Illinois, have invented a certain new and useful Improvement in Call-Registers, and declare the following to be a full, clear, and exact description of the same, such as will enable others skilled in 10 the art to which it pertains to make and use the same, reference being had to the accompanying drawings, which form a part of this specification.

Our invention relates to mechanisms for 15 registering the number of calls made at a subscriber's station and has for its object to improve such mechanisms so as to prevent misunderstandings between the central operator and the subscriber in the matter of 20 registering.

The type of mechanism to which our invention relates is that wherein the registering mechanism is operated manually by the subscriber, central being notified that the 25 register has been moved one step by means of a signaling device associated with the register.

In accordance with our invention, we so 30 arrange and connect the registering devices and the signaling devices that the completion of a registering movement insures the giving of a signal while, on the other hand, no signal can be given until a call has been registered. Consequently there can be no 35 dispute between a subscriber and the telephone operator for the registration and the signal are completed together and one cannot be made without the other.

The various features of novelty whereby 40 our invention is characterized will hereafter be pointed out with particularity in the claims; but, for a full understanding of our invention and of its object and advantages, reference may be had to the following detailed description taken in connection with the accompanying drawings, wherein:

Figures 1, 2, 3 and 4 are views showing, respectively, the side, the top, and the two ends of a device embodying our improvements, the inclosing casing being omitted; 50 Figs. 5, 6, and 7 are sections, on an enlarged scale, on line X—X of Fig. 1, each of these figures showing the parts in a position differing from that in the other figures; and Fig. 8 is a view similar to 55 the left-hand end of Fig. 1 on an enlarged scale.

Referring to the drawings, A represents a frame in which is mounted a shaft B, on which are loosely mounted a series of registering disks, C¹, C², C³, and C⁴. On one side of the disk C¹ is a ratchet wheel D having the same number of teeth as there are numerals or other indicating devices on the periphery of the disk; E is an operating lever for the register, loosely journaled upon the shaft B and projecting upwardly through an opening α in the frame; F is a spring suitably arranged to hold the lever in one extreme position. Upon an arm E¹, 60 projecting laterally from the lever, is a spring-held pawl G which cooperates with the ratchet wheel D; H is a pawl engaging with the ratchet so as to hold it yieldingly in any position to which it may be moved. 65 Whenever the subscriber makes a call, he moves the lever from the position indicated in Fig. 5, to that indicated in Fig. 7. This turns the first disk of the series through one 70 of the steps and, when the lever is released, the spring returns it to its normal position, 75 while the disk remains locked by means of the pawl H.

It is necessary that the central operator be apprised of the completion of a registration, 80 and it is, therefore, usual to have some sort of "buzzer" associated with the registering mechanism so as to make and break a circuit and give an audible signal at the central station when the registering mechanism is operated. It is very desirable that the signaling device be so arranged that it will operate with certainty whenever the register has 85 been moved forward one step, and, furthermore, that the signal cannot be given before the registering lever has been moved its full 90 stroke. It is evident, however, that, even with these positive safe-guards, occasion might arise where the subscriber would move the operating lever through only a part of its working stroke and then, seeing it return to its normal position, would contend that he had registered, even though no signal was heard by the operator. In accordance with our invention, therefore, we 95 provide not only a construction which will signal and register positively, and in such a manner that no signal can be made without registering, or vice versa, but one in which the operating lever must be actuated through 100 105 110

a full stroke before it will return to its normal position, so that, if the subscriber releases the lever before it has completed its stroke, he will have positive evidence that he 5 did not register or signal.

The signaling device includes a stationary contact piece I and a movable contact piece J. The member J is preferably made of spring metal secured at one end to the frame 10 and having its other end free so as to permit it to vibrate under proper conditions. Since the present invention is not concerned with the particular form of signaling arrangement, no further description thereof, with 15 the exception of the member J, will be given. The resilient contact-maker is positioned adjacent to the plane in which the lever E moves. The lever E is provided with a second laterally-projecting arm E² which extends into proximity to the member J. Projecting from the edge of the member J, nearest the operating lever, is an ear j which overlaps the free end of the arm E². The major portion of the ear j lies parallel of 20 the plane of movement of the arm E², but at its lower end it is curved or bent laterally, as at j¹, and at its upper end it is also curved or bent laterally, but in the opposite direction, as at j². When the arm E² moves toward the ear from below, the portion j¹ guides it to the rear of the ear as viewed in Fig. 5; but, when the arm moves toward the ear from the opposite direction, the portion j² guides the arm toward the front of the ear; 25 as viewed in Fig. 5. Consequently, when the lever is moved through its working stroke, the arm E² passes along one side of the ear and holds the movable contact member positively out of engagement with the 30 fixed contact member, so that a signal cannot be given until the lever has been moved far enough to carry the member E² above the portion j², namely, until the lever has completed its working stroke. Near the upper 35 end of the ear j, and directly beneath the curved portion j², is a laterally-projecting lip j³ extending in the same direction as the part j². The parts are so proportioned that shortly before the operating lever reaches 40 the end of its working stroke, the arm E² rises above the lip j³ and the resiliency of the member J causes this lip to be carried laterally into the plane of the arm, so that the member J and its lip act as a spring pawl to 45 prevent the return of the actuating lever. This condition is illustrated in Fig. 6. When the lever is moved from the position indicated in Fig. 6 to that shown in Fig. 7, the end of the arm E² rises above the part j³ 50 so that, upon release of the lever, the arm engages with the upper side of the curved portion j² and deflects the member J laterally so as to permit the arm to pass down the front side, as viewed in Fig. 6. During its 55 downward passage, the arm engages with

the curved portion j¹ and deflects the member J still farther; and, as soon as the arm passes below the lower edge of the portion j¹, the member J begins to vibrate. The locking of the lever against return may, of course, take place at any point of its working stroke, but we prefer to have it occur near the end of the working stroke, not only because of the greater danger of misunderstandings if the lever is moved so as almost to complete its working stroke, but for a further reason which we will now describe. 70

The meter which we have illustrated is of the type wherein the reading is taken at the central station through electrical connections between the register and the central station. For the purpose of making these readings from a remote point, each of the disks of the register is provided with a series of projecting ribs of varying lengths, 75 as indicated at c, c¹, c², and c³. Directly beneath the shaft of the registering mechanism is a second shaft K. The shaft K is provided with a spiral groove k which makes but few turns throughout the length 80 of the shaft. 90

L indicates a traveling-block arranged upon the shaft K and carrying a switch mechanism M which includes a contact-maker m, projecting into proximity to the disks. When the shaft K is rotated, the block or carrier L is caused to travel from one end toward the other and the contact piece m engages with each of the ribs which happens to lie within its path. Whenever, 100 during movement of the block or carrier in one direction, the contact piece engages with one of the ribs, a circuit is closed and, by means of a suitable recording mechanism at the central station, a record may be made 105 of the exact condition of the register. In Fig. 5, the condition of the parts is such that the rib c³ on the first disk lies in the path of the contact piece m, while in Fig. 7 the rib c³ has passed beyond the range of 110 the contact piece. We prefer to arrange the lip j³ on the member J so that just before the end of the rib c³ moves out of the path of the member m, the lever is locked so that it cannot be returned to its normal position 115 without completing its stroke. Consequently, if a reading at this time were taken; from the central station, it would still be correct, corresponding to the reading which would have been given before the register 120 was partially operated. The shaft K may be operated so as to move the carrier L from the left-hand end of the device, as it appears in Fig. 1, to the right-hand end by means of a suitable key, not shown, which 125 actuates a segment N, meshing with a pinion k¹ on the end of the shaft. During this rotation of the shaft, a spring O is wound up. Upon release of the key which actuates the segment, the spring O turns the shaft in the 130

opposite direction and returns the carrier to the starting point. We prefer to provide a suitable escapement device P on the end of the shaft opposite that on which the pinion is located.

5 What we claim is:

1. In combination, a registering device, a traveling contact, a series of contacts associated with said device and adapted to operate with said traveling contact to produce an indication of the condition of the device, manually controlled mechanism for moving said device step by step, and means for locking said mechanism against return 10 to its normal position without completing the actuation of the device just before the changing of the condition of the contacts associated with said device.
2. In combination, a registering device, an operating lever, connections between said operating lever and said device for moving said device step by step, a contact arranged to be moved past said device, a contact carried by said device in position to be engaged 15 by the aforesaid contact in one position of said device and to be out of the path of said contact in the succeeding position of said device, and means for locking said lever so as to prevent it from returning to the starting point without completing its working stroke just before the contact on said device is carried out of the path of the co-operating contact.
3. In combination, a registering device,

a signal-controlling device including a resilient contact-maker, an operating member for said device, an arm on said member for acting upon said contact-maker after the completion of the working stroke of said member so that the contact member is deflected and then released so as to allow the said contact member to vibrate, and means on said contact-maker for engaging with said arm so as to lock said member against return movement after it has passed a predetermined point in its working stroke until after it has completed that stroke.

4. In combination, a registering device, a signal-controlling device including a resilient contact-maker, an operating lever for said device, an arm projecting from said lever adjacent to said contact-maker, said contact maker having separated oppositely-inclined portions which serve to deflect it to one side of the arm or the other depending upon the direction in which said arm approaches, and said contact-maker having a shoulder in position to move beneath said arm and prevent return motion of the lever when the lever is actuated so as to partially shift said registering device.

In testimony whereof, we sign this specification in the presence of two witnesses.

HENRY P. CLAUSEN.
